GARAGE DOOR OPENING AND CLOSING APPARATUS

Joseph J. Kramer, National City, Calif.

Application February 1, 1936, Serial No. 61,905

7 Claims. (Cl. 268—68)

My invention relates to a garage door opening and closing remote control apparatus, and the objects of my invention are:

First, to provide an apparatus for opening and closing double hinged garage doors from the driver's seat of an automobile when either entering or leaving the garage.

Second, to provide an apparatus of this class in which the doors are securely latched in either open or closed position and may be locked in closed position by said apparatus.

Third, to provide an apparatus of this class in which the remote control portion is positioned up over head out of the way.

Fourth, to provide an apparatus of this class in which the apparatus must be unlatched through the means of the remote control before it is operative either for opening or closing the doors.

Fifth, to provide an apparatus of this class which is manually operated and requires no power mechanism in connection therewith.

Sixth, to provide an apparatus of this class by means of which the double doors on each side are operated in unison and therefore uniform opening and closing of the doors is provided.

Seventh, to provide an apparatus of this class which is very efficient in its action and which will not readily deteriorate or get out of order.

With these and other objects in view as will appear hereinafter my invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a fragmentary elevational view of the garage doors and apparatus in connection therewith showing the doors closed and looking outwardly from the inside of the garage taken from the line 1—1 of Fig. 5; Fig. 2 is an enlarged fragmentary perspective view of the door engaging and operating mechanism as shown in Fig. 1 of the drawings; Fig. 3 is a sectional view from the line 3—3 of Fig. 1 showing the doors in their open position; Fig. 4 is a detailed elevational view from the line 4—4 of Fig. 3 of the door control mechanism with the doors in their opened position as distinguished from the same structure in Fig. 1 of the drawings; Fig. 5 is a sectional view from the line 5—5 of Fig. 1 showing some of the parts and portions in elevation to facilitate the illustration; Fig. 6 is an en-

larged detailed sectional view from the line 6—6 of Fig. 5 showing some of the parts and portions in elevation to facilitate the illustration; Fig. 7 is a fragmentary, enlarged perspective view of the door control arm and door control dogs in their latched or neutral positions; Fig. 8 is a similar view showing the dogs in position right after closing the same; Fig. 9 is an enlarged sectional view from the line 9—9 of Fig. 5 showing some of the parts in elevation to facilitate the illustration; Fig. 10 is an enlarged sectional view from the line 10—10 of Fig. 5; Fig. 11 is a sectional view from the line 11—11 of Fig. 10; and Fig. 12 is an enlarged sectional view from the line 12—12 of Fig. 1.

Similar characters of reference refer to similar parts and portions throughout the several views of the drawings.

The double door sets 1 and 2, door control arm 3, door control arm handle 4, door control dogs 5 and 6, door control dogs supporting plate 7, lever 8, bifurcated lever 9, T members 10 and 11, lever 12, trip member 13, rods 14 and 15 and frame F constitute the principal parts and portions of my garage door opening and closing remote control apparatus.

The double door sets 1 and 2 each consist of two doors hinged together at their adjacent sides by means of hinges 2a and one door of each set is hinged to the garage door frame as shown best in Fig. 3 of the drawings by means of hinges 2b. The door sets 1 and 2 open from the center simultaneously and swing outwardly, each door set folding together as it swings open as shown in Fig. 3 of the drawings. The doors are guided by an overhead trolley T with which pulleys 2c are supported on the inner upper corners of the door sets 1 and 2. Mounted on the adjacent edges of the door sets 1 and 2 near their upper edges are bars 1d and 2d which overhang the edges of the doors for holding them in their proper relation to each other when closed, shown best in Fig. 1 of the drawings.

The doors are controlled from the driver's seat of the automobile by means of the door control arm handle 4 which is tubular as shown best in Figs. 5, 6 and 10 of the drawings. It is pivotally connected and supported on the door control arm 3 by means of bracket member 3a so it will swing from side to side as shown by dotted lines in Fig. 5 of the drawings. It is provided on its lower end with a threaded slotted portion 4a on which is mounted a nut 4b, see Fig. 6 providing means for securing the telescoping member 4c therein in different elevated positions. This

member 4c is provided on its lower end with a flange 4d all as shown best in Figs. 5 and 10 of the drawings. Extending through the members 4 and 4c is a shaft 4e which is provided 5 on its lower end with a disk 4f and a loop member 4g which serves as a handle for turning the shaft 4e and as a means for latching said shaft 4e. The two disks 4d and 4f have holes therein that coincide when the disks are in neutral position adapted to receive a padlock as shown in 10 Fig. 11 for locking the apparatus against opening the door. Connected at the upper end of the shaft 4e is a disk 4h which is mounted in a recess 3b in the arm member 3, all as shown best 15 in Figs. 5 and 9 of the drawings, so that the disk 4h revolves with the shaft 4e. Connected to this disk 4h at its one end is a flexible rod 3c which is pivotally connected thereto. This rod 3c extends longitudinally through the arm 3 near its 20 upper surface to its opposite end and is secured to the one end of the plate 7 as shown best in Figs. 5, 7, and 8, so that when the shaft 4e is rotated the plate 7 which is secured to this lever arm 3 by a pin through the slots 7a and 7b will 25 shift longitudinally upon the arm 3. The end of the arm 3 is slotted at 3d as shown by dotted lines in Figs. 7 and 8 of the drawings, and the plate 7 which is also slotted at 7c is positioned directly above said slot 3d in the arm member 3. 30 Vertically shiftable within these slots 3d and 7c are the dogs 5 and 6 which are supported by means of pin 3e but are shiftable upwardly and downwardly thereon because of slots 5a and 6a through which the pin 3e extends. In order to 35 lift the dog 5, plate 7 is shifted by turning the shaft 4e until the plate 7 engages the dog 5 at 5b and then by pulling down on the arm handle 4 causes the outside end of the lever 3 to move downwardly and the inside end to move 40 upwardly since said arm 3 is pivoted at 3e as shown best in Figs. 5, 7, and 8 of the drawings. Also by shifting the plate 7 to the proper position, the dogs 6 can likewise be lifted. However, 45 both dogs 5 and 6 cannot be lifted at the same time. Pivotally connected to the lower end of the dog 5 is the lever arm 9, and pivotally connected to the lower end of the dog 6 is a bifurcated lever arm 8 as shown best in Figs. 7, 8 and 12 of the drawings, it being noted that the arm 8 is positioned intermediate the extended 50 elements of the bifurcated lever 9 as shown best in Figs. 7 and 12 of the drawings. These levers 8 and 9 are pivotally supported intermediate their ends by means of a pin 8a supported by brackets 8b on the frame member F as shown best in Fig. 1 of the drawings. Pivotally connected to one blade of the bifurcated lever 9 at its one end 55 is a link member 10a and to the other blade of said bifurcated member 9 a link member 11a and pivotally connected to the lever 8 are link members 10b and 11b. The links 10a and 10b are connected to the T member 10, and the links 11a and 11b are connected to the T member 11, all of said links 10a, 10b, 11a, and 11b are 60 slotted where they connect with the T members and are secured to said T members by means of pins through said slots. Both T members 10 and 11 are pivotally connected to the frame of the garage by a common pin 10c. Thus it will 65 be noted that as the dog 6 is lifted lever 8 will draw down the ends of rods 10b and 11b thereby causing the T member 10 to pivot about 10c counter-clockwise and T member 11, clockwise. If the dog 5 is lifted by lever 3, bifurcated lever 70 9 will draw down on the ends of links 10a and

11a thereby causing the T member 10 to pivot clockwise and T member 11 counter-clockwise or just the reverse motion that would be caused by lifting the dog 6.

The lower end of the T member 10 is connected 5 to the rod 14 at its one end. To the opposite end of the rod 14 is connected a trip member 13. This trip member 13 is pivotally mounted upon an L shaped member 13a by means of pin 13b shown best in Fig. 2 of the drawings. And this 10 L shaped member 13a is free to turn as a hinge on member 2e, which member 2e is mounted on one of the doors 2 as shown best in Fig. 3 of the drawings. This trip member 13 because of its hinged relation with the door member 2 is in 15 a position shown in Fig. 1 when the doors are closed and in the position shown in Fig. 3 when the doors are open. Therefore, to open the doors, the plate 7 is positioned to engage the dog 5 by turning the shaft 4e by its end 4f and pulling 20 down on the arm 3 by means of the handle 4, thereby lifting the dog 5 and causing the T member 10 to move clockwise and the T member 11 to move counter-clockwise. The rod 15 will follow the T member 11 and the rod 14 will follow the T member 10. As the rod 14 moves the trip 13 will press down on the pin 12a causing the lever 12 to pivot at 12b and lift the bolt 12c free from engagement with the door set 2 as 25 shown in Fig. 2, at the same time acting concurrently with rod 14 is trip 13, L member 13a and its hinge 13b as shown in Fig. 2 of the drawings. The door set 2 is fully opened when the doors have folded against each other as shown best in Fig. 3 of the drawings and when in this 30 fully opened position they are latched in such position by the members 12c and 12d, the end of the bar 2d engaging notches 12h in the end of the bar 12i which is secured to and is a portion of the lever 12, thus the members 12c and 12d latch the doors open as shown in Fig. 3 of the drawings. Therefore the doors cannot be closed until these two members 12c and 12d became disengaged. The doors cannot be closed until the notch 12h is disengaged from the member 2d. This is accomplished by setting the plate 7 to engage the dog 6 and drawing down on the lever 3. This reverses the movement that the rod 14 had when opening the door 2 and also causes the trip 13 to press up against the lever 12 thereby raising the member 12i because 40 the lever 12 pivots about its axis 12b and releasing the notch 12h from the member 2d. And since the rod 14 is pushing in the reverse direction required to open the door set 2, will cause 45 said door set to swing about its hinge 2b to its 50 closed position.

It will be here noted that applicant has not 55 fully disclosed the door operating structure at the left side of the door set number 1, because 60 the construction is exactly the same, and the mode of operation is exactly the same as that disclosed in connection with the door set number 2, so that the two door sets 1 and 2 operate by opening and closing in the same manner, operated separately as follows: The doors of set 65 1 by the T member 10 and rod 14 and the doors of set 2 by the T member 11 and rod 15 and their similar connecting members.

Though I have shown and described a particular construction, combination, and arrangement of parts and portions I do not wish to be limited to this particular construction, combination and arrangement but desire to include in the scope of my invention, the construction, combination and 70 75

arrangement substantially as set forth in the appended claims.

Having thus described my invention, what I claim as new and desire to secure by Letters Patent is:

1. In a garage door opening and closing remote control apparatus, the combination with double folding hinged doors, of an arm member pivotally mounted on the door frame above said door and extending forwardly of the garage, a handle member depending therefrom at its outwardly extending end, a shaft revolvably mounted in said handle member, a latch in operative relation with said shaft, and lever and link means connecting with said arm controlled by said latch and connected with the hinged folded door member of said folding doors.

2. In a garage door opening and closing remote control apparatus, the combination with double folding hinged doors, of an arm member pivotally mounted on the door frame above said door and extending forwardly of the garage, a handle member depending therefrom at its outwardly extending end, a shaft revolvably mounted in said handle member, a latch in operative relation with said shaft, lever and link means connecting with said arm, controlled by said latch and connected with the hinged folded door member of said folding doors, and said link and lever means including pairs of identical members connected with said doors whereby said doors are simultaneously operated.

3. In a garage door opening and closing remote control apparatus, the combination with double folding hinged doors, of an arm member pivotally mounted on the door frame above said door and extending forwardly of the garage, a handle member depending therefrom at its outwardly extending end, a shaft revolvably mounted in said handle member, a latch in operative relation with said shaft, lever and link means connecting with said arm, controlled by said latch and connected with the hinged folded door member of said folding doors, said link and lever means including pairs of identical members connected with said doors whereby said doors are simultaneously operated, and latch means in connection with said door control means for latching said doors in closed position.

4. In an apparatus of the class described, the combination with double folded doors on opposite sides of a garage door opening, of bolt and lever means in connection with said doors for latching said doors in closed position, lever and notch means in connection with said doors for latching said doors in open position, and remote control and latch means in cooperative relation therewith extending forwardly above said garage doors and

accessible to the driver of a vehicle from the seat of the vehicle consisting of a forwardly extending door control arm member, a handle extending from the extended end thereof, and latch means revolvably connected with said handle.

5

5. In an apparatus of the class described, the combination with double folded doors on opposite sides of a garage door opening, of bolt and lever means in connection with said doors for latching said doors in closed position, lever and notch means in connection with said doors for latching said doors in open position, remote control and latch means in cooperative relation therewith extending forwardly above said garage doors and accessible to the driver of a vehicle from the seat of the vehicle consisting of a forwardly extending door control arm member a handle extending from the extended end thereof, latch means revolvably connected with said handle, and means operatively connecting said latch means with door control means.

10

6. In an apparatus of the class described, the combination with double folded doors on opposite sides of a garage door opening, of bolt and lever means in connection with said doors for latching said doors in closed position, lever and notch means in connection with said doors for latching said doors in open position, remote control and latch means in cooperative relation therewith extending forwardly above said garage doors and accessible to the driver of a vehicle from the seat of the vehicle consisting of a forwardly extending door control arm member, a handle extending from the extended end thereof, latch means revolvably connected with said handle, means operatively connecting said latch means with said door control means and opening and closing selective means in connection therewith.

15

7. In a garage door opening and closing remote control apparatus, the combination with double folding hinged doors of an arm member pivotally mounted on the door frame above said doors and extending forwardly of the garage, a handle member depending therefrom, at its outwardly extending end, a shaft revolvably mounted in said handle member, a latch in operative relation with said shaft, lever and link means connecting with said arm, controlled by said latch and connected with the hinged folded door member of said folding doors, said link and lever means including pairs of identical members connected with said doors whereby said doors are simultaneously operated and latch means in connection with said door control means for latching said doors in closed position and lever and notch means in connection with said doors for latching said doors in open position.
